CLAIM

(22) Filed: **Jan. 25, 2002**

The ornamental design for a vehicle wheel lug-nut having
frontal indicia, as shown and described.

(51) LOC (7) Cl. **08-08**

DESCRIPTION

(52) U.S. Cl. **D8/397**

FIG. 1 is a perspective view of a vehicle wheel lug-nut
having frontal indicia showing my new design;

(58) Field of Search D8/382, 397, 399;
411/81, 98, 103, 106, 145, 146, 172, 179,
197, 204, 248, 337, 338, 368, 371.2, 372.5,
418, 427, 429, 430, 431, 432, 436, 437,
500, 511, 512, 514, 531, 532, 533, 535,
536, 537, 538, 542, 544, 918, 928; 70/229;
301/35.623, 111.01

FIG. 2 is a right side elevational view thereof; the left side
being a mirror image;

FIG. 3 is a top plan view thereof, the bottom being a mirror
image;

FIG. 4 is a front elevational view showing the location of a
frontal indicia; and,

FIG. 5 is a rear side elevational view thereof.

The word logo is shown in broken lines in FIGS. 1 and 4 to
indicate that a specific Logo pertaining to a specific manu-
facturer or distributor will be included in the final vehicle
wheel lug-nut. The broken lines form no part of the claimed
design.
